UNITED STATES PATENT OFFICE.

DE BERT HARTLEY, OF CHICAGO, ILLINOIS.

FLYING-MACHINE.

1,068,652.

Specification of Letters Patent.

Patented July 29, 1913.

Application filed April 11, 1912. Serial No. 690,108.

To all whom it may concern:

Be it known that I, DE BERT HARTLEY, a citizen of the United States, and a resident of Chicago, in the county of Cook and State 5 of Illinois, have invented certain new and useful Improvements in Flying-Machines; and I do hereby declare that the following is a full, clear, and exact description thereof, reference being had to the accompanying 10 drawings, and to the characters of reference marked thereon, which form a part of this specification.

This invention relates to improvements in flying machines of that class originally 15 known as aeroplanes, and the invention relates principally to the general type of machine illustrated in my prior application for U. S. Letters Patent, Serial No. 584,968, filed on the 3rd day of October, 1910, in 20 which laterally extending, pivoted planes or wings are employed for sustaining, balancing and directing the course of the machine. While my invention is shown as embodied in the type of machine referred to it will be 25 understood that the invention is capable of a variety of mechanical expression, one of which, for the purpose of illustrating the invention is shown in the accompanying drawings. It will be furthermore understood 30 that as to certain features of the machine, they are adaptable to other types of flying machines. It will be understood therefore that the drawings and the description of the particular construction 35 herein shown are employed for the purpose of facilitating the description of the invention, and are not employed to define the limits of the invention, reference being had 40 for this purpose to the appended claims.

One of the features of the present invention is embraced in a main or central plane which, in addition to the usual parabolic curve in the line of flight, is dihedrally angled or curved in a direction transverse 45 to the line of flight so as to thereby give the machine an improved stabilizing action. This feature of my invention may be expressed in forms of machines other than those having the pivoted or tilting wings 50 such as herein shown.

A further feature of the invention resides in the construction and arrangement of the pivoted wings or planes, with means for operating same, so arranged as to warp 55 or twist said wings to vary the angle of incidence from the inner ends thereof to the

extreme points of the planes, either for changing the course of the machine or for varying its speed. The operating mechanism to twist or warp the wings may be operated either independently or simultaneously to effect warping of the wings or simultaneous warping thereof, and such warping may be effected simultaneously with or independently from the tilting movement of 60 the wings. In this connection I have provided a novel means for trussing the pivoted planes or wings, arranged to give the desired strength to the wings while permitting freedom of action for warping. 65

A further feature of the invention resides in raising the pivots at the rear or following edges of the wings above said following edges, whereby when the wings are tilted to swing the outer ends thereof upwardly, 70 the following edge of the wing or plane is given an outward movement, or away from the longitudinal center of the machine, which increases the angles of incidence of 75 the wings so operated and increases the resistance to flight, for balancing and turning purposes. 80

A further feature of the invention resides in connecting the front elevator with the pivoted wings or planes in such way that 85 the said elevator is automatically operated to raise and lower the same when the wings are swung on their pivots, and resides further in connection of both the elevator and the following plane or rudder to the pivoted 90 wings, all being placed under the action of controlling springs or their equivalents carried by the main or central frame of the machine. 95

A further feature of the invention resides in providing foot actuated means for giving swinging movement to the pivoted planes or wings, and this feature of the invention may be combined with the means for twisting or warping the wings whereby the swinging 100 movement of the wings may occur simultaneously with or independently of the warping thereof.

A further feature of the invention resides in the arrangement of the centrally arranged, front and rear, starting and alighting wheels to support the machine when alighting and also while the machine is gaining momentum in starting, for flight one of said wheels, the forward wheel as 110 herein shown, being adapted to be drawn upwardly into the frame, when the machine

is at rest on the ground, so that the frame which is made relatively wide at its base, constitutes a stable support. The said supporting and alighting wheels are mounted with suitable springs or equivalent devices to absorb shocks brought thereon in the landing of the machine on the ground. The arrangement of the supporting wheels one in front of the other centrally of the machine, as distinguished from the widely separated supporting wheels, is advantageous, inasmuch as such arrangement permits the machine to be started from and landed on more or less uneven surfaces with less liability of racking the machine. The forward, centrally disposed supporting wheel may constitute a rolling support on which the machine may be trundled, when the rear end of the machine is raised, in the manner of a wheel barrow to thereby render it practical for one person to readily move the machine from place to place on the ground. The main frame is fashioned at its lower side to constitute a buoyant body so as to enable the machine to float in the event of alighting on water.

A further feature of the invention resides in an improved means of connecting a single motor with two oppositely rotating propellers without the necessity of using cross chains or like connections, the propellers being arranged at the front of the machine in position to give a steadyng effect to the machine.

The invention embraces other improvements in flying machines as will hereinafter more fully appear and which are pointed out in the appended claims.

In the drawings; Figure 1 is a plan view of a flying machine embodying my invention. Fig. 2 is a rear edge view of one of the pivoted planes or wings. Fig. 3 is a detail section on the line 3—3 of Fig. 2. Fig. 4 is a detail section on the line 4—4 of Fig. 3. Fig. 5 is a plan view of the parts shown in Figs. 3 and 4, on the line 5—5 of Fig. 4. Fig. 6 is a front elevation of the machine, with parts broken away. Figs. 7 and 8 are detail sections on the lines 7—7 and 8—8 of Fig. 6. Fig. 9 is a vertical section of the general line 9—9 of Fig. 6. Fig. 10 is a detail illustrating the mounting for the starting and alighting wheels. Fig. 11 is a detail illustrating the cushioning or shock absorbing device for the rear starting and alighting wheel. Figs. 12, 13 and 14 are views, diagrammatic in their nature, illustrating the manner in which the wings or pivoted planes are warped, and the mechanism for warping them. Fig. 15 is an enlarged detail illustrating the mounting for the pivoted planes and also the mechanism for operating the planes, and illustrating also the mounting for the front starting and alighting wheel. Figs. 16 and 17 illustrate

two positions of a part of the mechanism for controlling the front elevator.

As shown in the drawings, 20 designates the central or body plane, supported on a central trussed frame, hereinafter to be described. 70

21, 21 designate laterally and oppositely extending pivoted planes or wings which are arranged transversely to the line of flight and are pivoted nearest their inner end to the frame of the main or central plane, the pivots of said wings 21 being arranged at the front and rear margins thereof and trending in the line of flight of the machine. 75

22 is a vertically swinging elevator or advancing plane arranged in front of the machine for the purpose of steering and supporting the machine in vertical directions, and 23 is a horizontal following plane or rudder which is hinged to the frame at the following edge of the main plane for supporting the machine and steering the same in lateral directions and arranged to modify the vertical direction or line of flight of the machine. 80 90

The parts referred to are arranged generally like the similar parts of the machine illustrated in my aforesaid application. The controlling levers 24 for the following plane or rudder are pivoted to the frame at 35 and 95 are adapted for connection with the lateral wings and the following plane or rudder in a manner generally similar to the construction shown in my prior application.

The main or central plane 20 is stretched 100 across and is supported on a rigid, trussed central frame consisting, as best shown in Figs. 6 and 9, of front and rear trusses arranged transverse to the line of flight, each comprising an upper member 26, a lower 105 member 27, with vertical and horizontal struts 28, 28 rigidly connecting the same. Said frame is formed with front and rear extension members 29, 30 which are brought together at 31 at the sides of the frame to 110 carry hinge elements to which the wings 21, are pivoted.

The main plane 20 is parabolically curved in the line of flight of the machine as shown in Fig. 9, and is also dihedrally angled or 115 substantially so transverse to the line of flight, so as to thereby give greater stability to the main plane, as shown in Fig. 6. The said trussed frame is provided at its rear and front margins with laterally separated converging frame members 33, 33 and 34, 34 respectively, as shown in Figs. 1 and 9. At the points of convergence of the members 34, 34 are formed the bearings 35 in which are pivotally mounted the following plane 120 or rudder actuating levers 24.

The forwardly extending members 33, 33 of the main frame are joined at their forward ends to a transverse member 36 which carries a bearing 37 in which and a bearing 130

38 at the front side of the frame is mounted a tubular, rotative shaft 39 which constitutes part of the driving mechanism for propellers 40, 40 located at the front of the machine. Said driving mechanism, which is operated from a single motor 41 that is supported in the frame beneath the main plane, embraces further a shaft 43 mounted within the tubular shaft 39. The said tubular shaft 39 carries at its outer end a sprocket wheel 44 which is connected by a chain 45 with a sprocket wheel 46 that is fixed to the shaft 47 of one of the propellers 40, said hollow shaft being supported on a bearing shaft 48 fixed to and extending forwardly from the frame of the main plane. The inner shaft 43 is provided with a sprocket wheel 50 that is connected by a sprocket chain 51 with a sprocket wheel 52 of a similar shaft 53 which carries the other propeller 40. The said hollow shaft 39 is provided at its rear end with a beveled gear wheel 54 (Figs. 7 and 9) and the inner shaft 43 is provided with an oppositely facing gear wheel 55, and said beveled gear wheels mesh with a beveled gear wheel 56 which is fixed to and rotates with the moving part of the motor 41; said motor being herein shown as comprising a horizontally rotative, multi-cylinder gasoline engine with said gear wheel 56 fixed to a rotative part of said engine. With the construction described it will be evident that when the engine rotates it serves to rotate the propellers 40 in opposite directions.

The elevator 22 is pivotally mounted at 58 to swing vertically, the rigidly connected frame members 59, 60 over which the cloth or other material is stretched to produce the plane being rigidly connected at the corners of the elevator with each other through fittings 61 that constitute parts of the elevator hinge.

The rigid main frame comprises, in addition to the members described, the upright, curved posts 65, 65 connected at their upper ends to the frame of the main plane in any suitable manner and connected at their lower ends to the members 66 which extend between and connect the front and rear trusses of the main frame. The said posts are rigidly connected by the transverse frame members 67, 68 (Fig. 15). Said posts constitute, in addition to fixed members of the frame, guide members for pivoted wings, and means for supporting controlling springs for the wings as will hereinafter more fully appear.

The central portion of the frame, bounded by the members 66 and the posts 65 is enclosed by the housing 70, shown best in Figs. 6 and 9, having substantially straight side portions and forwardly and rearwardly inclined bottom portions, the housing enclosing the motor, the seat 71 (Fig. 9) for the aviator and portions of the controlling

mechanism for operating the machine, as will hereinafter more fully appear. The said housing is made of any suitable rigid material and is inclosed at its lower side so as to constitute a buoyant body to support the machine on water in case the machine should happen to alight on a body of water.

The machine is adapted to be supported on front and rear supporting wheels 75, 76, respectively. The said wheels are arranged, one in front of the other, at the longitudinal center of the machine. The rear wheel may be a broad faced wheel or a double wheel, the latter being shown in Fig. 11. The said rear wheel is spring mounted to cushion the rear side of the machine frame when alighting. As herein shown the axle 77 of the rear wheel is mounted in the free ends of the arms 78 that are hinged or loosely connected to a cross bar 79 of the main frame. The bearing sleeve for the axle 77 is provided with an upwardly extending stem 80 which engages a tubular guide 81 that is hinged to a second cross bar 82 of the frame and braced therefrom by the braces 83. The said cross bars 82 and 79 are connected fixedly together by the struts 85, as best shown in Fig. 11. Interposed between the sleeve 81 and a shoulder on the stem 80, and surrounding said stem, is a spring 86 which normally holds the wheel in its downward position and against the action of which the said stem slides into said sleeve when the rear wheel is raised relatively to the main frame. With this construction, when the wheel 76 strikes the ground upon the alighting of the machine, the hinge connection of the arms or links 78 with the cross bar 79 permits the wheel 76 to swing upwardly against the action of the spring 86, and the sleeve 81 partakes of a like swinging movement so as to absorb the shock due to the contact of said wheel with the ground.

The wheel 75 normally occupies a downwardly opening recess 88 at the bottom of the housing 70, as best shown in Figs. 6 and 9, and is adapted to be projected below said housing when the machine is to alight and drawn into the housing after the machine has alighted or is in flight by means made as follows: The said wheel 75 is mounted on an axle 90 which extends between and is secured in any suitable manner to the lower ends of two upwardly opening tubular members 91, 91; and said axle is connected by links 92, 92 with the frame, being pivoted to the frame at the points 93. The said tubular members 91 are connected by a cross bar 95, and receive at their upper ends plungers 96, 96, which plungers bear upon compression springs 97, 97 within the tubular members that are interposed between the plungers and the bottoms of said tubular members. 99 designates an L-shaped lever that is pivoted at the end of its shorter arm to

he cross piece 67 of the main frame and is connected at the angle between its arms by the cross bar 100 to the plungers 96, 101 designates a headed rod that extends 5 through said cross bar 100, with its head bearing against the cross bar and extends freely through the cross bar 95 and is provided below said cross bar with a nut 102. When said lever 99 is swung upwardly it 10 acts, through the rod 101 to raise the tubular frame members 91 of the wheel mounting so as to draw the wheel 75 into the recess 88, this action compressing the springs 97. When the lever 99 is swung downwardly to 15 the position shown in Fig. 10 it permits the springs 97 to expand and to throw the wheel 75 downwardly to the position shown in Fig. 10 so as to permit the wheel to contact with the ground when the machine is starting or 20 alighting. When preparing to alight the said wheel 75 is thus projected downwardly, and after the machine has alighted the wheel is drawn upwardly so that the housing 70, which is relatively wide transversely 25 of the machine, constitutes means for supporting and steadyng the machine. When the machine is to be started the lever 99 is swung downwardly, thereby serving to raise the machine relatively to the wheel so as to 30 support the machine on said wheel and the rear wheel 77.

The arrangement of wheels, disposed at the longitudinal center of the machine, as shown, enables the machine to rise from and 35 alight upon uneven surfaces without the objectionable racking of the machine such as occurs when the supporting wheels are laterally separated substantial distances apart. Moreover the lever arrangement for shifting 40 the wheel 75 upwardly and downwardly is such as to lock the wheel in either of these positions. Therefore when the wheel is projected downwardly from the housing it may serve as a means by which to trundle the machine from place to place, in the manner of a 45 wheel barrow, it only being necessary for the person thus handling the machine to raise the rear end sufficiently to throw the entire weight upon the front wheel 75 and 50 to propel the machine, either by pulling or pushing the machine, while resting on the single wheel 75. The said lever 99 is located so as to be readily accessible from the seat 71 so as to thereby enable the aviator to 55 readily control the position of the front wheel 75.

The pivoted planes or wings 21 are provided at their front and rear edges respectively with pivot members 105, 106 which 60 engage the pivot members or elements 31 carried by the extensions 29, 30 of the main frame, so that the said pivots trend in the direction of flight of the machine. The said wings are thus pivoted to the frame at 65 a distance from the inner ends thereof, sub-

stantially one third of the length of said wings from their inner ends, in the same manner as described in my aforesaid application as supporting and balancing wings or planes. The inner ends of said 70 pivoted planes are provided with guide lugs or extensions 107 which are recessed to engage over the upright posts 65 of the main frame to hold the wings laterally in place, and said posts are curved concentrically to 75 the pivotal axes of the wings or planes so as to maintain such guiding engagement in all positions of the wings or planes.

As a further and separate improvement, the hinge lugs or elements at the rear or 80 following edges of the pivoted wings are raised above said following edges, being herein shown as carried by stiffening truss members 109 fixed to the following edges of the wings, as best shown in Figs. 2, 12, 85 13 and 14. As a result of this construction and arrangement, when the outer ends of the wings are swung upwardly, the following edge of the wings moves outwardly from a normal position, so as to thereby increase the angle of incidence of the wings and therefore increase the resistance of the wings to forward flight or turning movement of the machine. The wings are independently operated. Thus if one only of 95 the wings be tilted upwardly at its outer end an added resistance will be thrown on the side of the machine so as to cause the machine to tend to turn about the plane or wing that is thus tilted upwardly. If both 100 wings be simultaneously tilted upwardly at their outer ends a breaking or retarding effect to forward flight is imposed on the machine which tends to reduce the speed, this action closely simulating the action of 105 the wing of a bird in arresting its flight preparatory to alighting. The said pivoted wings or planes operate under the control of springs 111 which are carried by or are mounted within the hollow posts 65 in a 110 manner generally similar to the machine shown in my aforesaid prior application, said springs tending to hold the pivoted wings or planes in normal position for flight, and the wings being tilted on their 115 pivots (either automatically or normally) in opposition to the action of said springs.

In addition to the means for controlling the said pivoted planes or wings to tilt the same upon their axes, the said wings are 120 so constructed, and are provided with actuating mechanism, to warp or twist the planes, such actuating mechanism, to warp or twist the planes being arranged to effect such warping or twisting of the planes 125 either simultaneously or independently of each other, and such warping action may occur simultaneously with or independently of the tilting movement of the wings. The means which I have herein shown to effect 130

this result are made as follows: The inner ends of the pivoted wings or planes are connected to the posts 65 through the medium of a system of quadrilaterally arranged levers 115, 116, 117, 118, one pair of levers being pivoted at 119 to the inner end of each wing or plane 21 at a point in front of the guide 107 and the other pair of said levers being similarly pivoted to each wing at a point 120 in rear of said guide 107. The said levers are pivoted at their inner ends at 121 to upper and lower bars 122 and 123. The upper bars 122 are connected, as by means of studs or pins 124, with follower blocks 125 in the upper ends of the hollow posts 65, above and engaged by the springs 111 within said hollow posts, the lugs 124 extending through slots in said guide posts. Thus the action of the springs is transmitted to the pivoted planes or wings in a manner to maintain said wings in normal operative position for flight, while permitting the outer ends of the wings to swing upwardly, as in the construction shown in my aforesaid prior application. The lower ends of the lower bars 123 are loosely connected to guide sleeves or collars 126 which surround and slide up and down on the posts. The tension of the springs 111 may be varied, as by means of adjusting screws 127 that are screw-threaded through plugs 128 fitted in the lower ends of the posts, said screws bearing at their upper ends against the lower ends of the springs. 130, 130 designate levers which are pivoted at 131 to the inner ends of the pivoted wing structure (Figs. 12, 13, 14 and 15) and said levers are connected by the links 132, 133 with the arms 122, 123 in the manner best shown in Figs. 12, 13 and 14. The said levers carry hand latches or pawls 135 which coöperate with curved rack bars 136 to lock the levers in different positions as best shown in Figs. 12, 13 and 14.

Fig. 12 shows the normal position of the wings and of the controlling mechanism therefor. When the lever 130 is thrown backwardly as indicated in Fig. 13, the advancing edge of the inner end of the wing is swung upwardly, and the following edge of the inner end is swung downwardly. By reason of the pivotal connection of the wing at its edges with the frame, and of the fact that the wing is somewhat flexible, the outer end of the wing is twisted or warped in positions reverse to the inner end thereof. In other words, while the advancing edge of the inner end of the wing has thus been thrown upwardly, the advancing edge of the outer end thereof is thrown downwardly, while the following edge of the outer end of the wing is thrown upwardly, giving a negative angle of incidence to the outer end of the wing. By reason of the fact that the greater length of the wing, or

substantially two thirds of such length, as herein shown, is outside of its pivots, the effect of the wing, as a whole, is that of a negative angle and if both wings are thus warped, they tend to give the machine a downward course or diving effect. If only one of the wings be thus warped and the other retains its normal position the machine will tend to turn about the latter wing to change its course.

When the lever 130 is swung from its normal position forwardly to the position shown in Fig. 14 the following edge of the inner end of the wing is thrown upwardly and the advancing edge downwardly, while the following edge of the outer end of the wing is thrown downwardly and the advancing edge is thrown upwardly. The angle of incidence of the outer end, or the greater portion of the wing length is thus increased and the downwardly drooping following edges produce a resistance to the forward movement of the machine which serves, when both wings are thus warped, as a brake to reduce the speed of the machine and, when one wing only is thus warped, to slow up the latter side of the machine, thereby giving the machine a tendency to turn about to the outer end of the wing so warped. The positions of the wings shown in Figs. 13 and 14 indicate extreme warped positions from normal and positions which will seldom occur in the use of the machine. It will be understood however that any intermediate deviation of the wings from the normal positions indicated in Fig. 12 to either of the positions shown in Figs. 13 and 14 will produce the effect described to a greater or less extent, depending upon the approach of such position to the extreme positions of the wings. It will be furthermore understood that the wings are capable of an infinite series of positions between the normal position and the extreme positions illustrated, and that, by reason of the independent warping and tilting action of the wings, and the corresponding movements of the elevators and following plane or rudder, the course and speed of the machine may be modified in an infinite variety of ways, so as to give an exceedingly delicate control to the machine. It will be observed that the wing warping mechanism, consisting of the quadrilateral system of levers shown and their actuating means is movable with the wings when the latter are swung on their pivots and such swinging or tilting movement of the wings has no effect on the wing twisting mechanism to change the relative positions of the elements of said mechanism.

The vertical swinging movement of the wings may be effected either by foot actuated means or by hand actuated means, and reference to the actuating means herein as

manually operated means is intended to include any volitional actuation of the wings on the part of the aviator, as distinguished from the automatic actuation of the wings due to the change of center of gravity of the machine, such as is more fully described in my aforesaid application.

As herein shown, and more fully illustrated in Figs. 9 and 15, the foot operated devices comprise stirrups 140, 140 which are pivoted at 141 to fixed parts of the machine frame connected to the lower cross brace 68 extending between the posts 65. The said stirrups have upwardly and forwardly extending arms 142, 142, to the upper ends of which are attached flexible strands or ropes 145, 145 which are trained about sheaves 146, 146 mounted in any suitable manner on said posts 65 or other fixed part of the machine. The said flexible strands are attached at their upper ends to the upper ends of the bars 122 of the wing warping mechanism. When the stirrups are pressed forwardly they serve, through the flexible strands or ropes 145 and the wing warping mechanism to draw downwardly the inner ends of the wings and to swing the outer ends of the wings upwardly, this movement taking place against the action of the springs 111. The positions of the wings thus maintained between the opposing action of foot pressure and said springs.

The rudder actuating levers 24, which may be connected to the rudder or following plane in the manner shown in my aforesaid prior application, are shown in Fig. 9 as extending forwardly beneath the main plane and extending through eyes 149, 149 carried by the upper ends of the bars 122 of the wing warping mechanism. The swinging movements of the wings are thus transmitted to the following plane or rudder to manipulate the same, as in the manner shown in my aforesaid prior application, or otherwise. The said wings, in addition to being strengthened by the trusses 109 at their following edges, are further stiffened or supported by a truss arrangement made, as follows: 150 designates a vertical post for each wing which extends a distance above and below the same in the plane of the pivots of said wing. 151, 152 designate flexible truss members arranged one pair above and one pair below the wing. Each pair of truss members consists of two flexible strands or wires attached in any suitable manner, at the inner corners of the wing, as at 153, 154, and attached in like manner at 155, 156 to the corners of the wings at the outer ends thereof. The intermediate parts of said truss strands or wires extend loosely through suitable guides at the upper and lower ends of the posts 150 so as to slide freely therethrough. Each truss wire or

strand of each pair is attached at one end to the inner end of the wing at one side edge of the latter, is carried through the guide of the post 150 and is attached at its other end to the outer end of the wing on the same side edge of the wing. Said wires or strands are shown as confined at the posts 150 between the ends of said posts and disks 158, 158 attached to the posts by means of the shanks 159, 159 of guide eyes 160, through which extend transverse flexible truss members 162, 162 that are attached at their ends to the planes at their advancing and following edges as best shown in Fig. 1. In order that the said flexible truss wires or strands 151 may pass freely through the guides at the ends of the posts 150, the said posts may be provided at their ends with the sleeves 165 formed with the curved guide surfaces 166, best shown in Fig. 5, about which the flexible truss members are trained. The arrangement shown and described constitutes means for trussing and strengthening the wings, while permitting the freedom of action required to warp or twist the wings in the manner described below.

The means herein shown for connecting the elevator 22 with the pivoted wings, to give the coördinating action to said parts, are made as follows: 170 designates an elevator controlling lever which is rigidly connected at 171 to the elevator in advance of its hinges 58, as shown in Figs. 1 and 9. Said lever extends rearwardly beneath the main plane and is provided at its rear end, within reach of the aviator with a hand piece 174 by which the elevator may be controlled. Extending transversely of the hand piece 175 and loosely connected thereto is a member 176, to the outer end of which are attached the flexible strands or cords 177, 177, which latter are attached at their lower ends to the inner ends of the wings. Through said connecting devices the swinging motion of the wings is communicated to the elevator to control the same. By reason of the connection of the elevator controlling lever with the wings through the member 176 (which has a swinging motion relatively to the lever 170) and flexible strands 177 the range of the movement transmitted to the elevator through the swinging movement of one of the wings through a given distance in one half the total movement transmitted to the elevator through the simultaneous movement of both wings through a like distance, as will be evident from an inspection of Figs. 16 and 17.

I claim as my invention:

1. In an aeroplane, the combination with a central frame, and a main plane supported thereupon, said plane being parabolically curved in the line of flight and dihedrally angled transversely to said line, of wings pivoted between their ends to said frame

- and extending laterally therefrom transversely to the line of flight and adapted to swing vertically, and means for actuating said wings to control the flight of the machine. 5
2. In an aeroplane, the combination with a central, trussed body frame having truss or bracing members on each side thereof, terminating in hinge elements arranged on axes trending in the line of flight, of wings borne by said hinge elements and a main plane supported by said frame and parabolically curved in the line of flight and dihedrally angled transversely thereto. 10
- 15 3. In an aeroplane, the combination with a central, trussed body frame having truss or bracing members on each side thereof, terminating in hinge elements arranged on axes trending in the line of flight and a main plane supported on said frame and parabolically curved in the line of flight and dihedrally angled transversely thereto, of lateral, vertically tilttable wings borne by said hinge elements, said wings being capable of being warped and means for tilting and warping said wings. 20
- 25 4. In an aeroplane, the combination of a central trussed body frame with truss or bracing members on each side thereof, terminating in hinge elements arranged on axes trending in the line of flight, lateral wings borne by said hinge elements and projecting inwardly therebeyond, and a main plane supported above the inner ends of said wings, and parabolically curved in the line of flight and dihedrally angled transversely thereto from a line median between and above said ends. 30
- 35 5. In an aeroplane, the combination of a central body frame having truss or bracing members on each side thereof terminating in hinge elements arranged on axes trending in the line of flight, lateral wings loosely pivoted on said elements to permit their being vertically tilted and to be warped or twisted, means to warp the wings simultaneously with or independently of their rising or falling movement, and a main plane carried by the body frame. 40
- 45 6. In an aeroplane, the combination of a central body frame having truss or bracing members on each side thereof, terminating in hinge elements arranged on axes trending in the line of flight, lateral, warpable wings pivotally mounted on said hinge elements and extending inwardly and outwardly therefrom, means to tilt said wings, means to warp said wings and a main plane supported by said body frame above the inner ends of said wings, and parabolically curved in the line of flight and dihedrally angled transversely thereto. 50
- 55 7. An aeroplane comprising a main plane, tilttable supporting wings and pivots trending in the line of flight upon which said
- wings are independently tilttable, said pivots being so arranged that when the outer ends of the wings are tilted upwardly the positive angle of incidence of said outer ends of the wings is increased. 70
8. An aeroplane comprising a main plane, laterally opposed, tilttable supporting and controlling wings, and pivots trending in the line of flight upon which the wings are independently tilttable, the pivots of each of said wings being located one at the advancing and the other at the following edge of each wing with the latter pivots raised above said following edge. 75
9. An aeroplane comprising a main plane, laterally opposed, tilttable supporting and controlling wings, pivots trending in the line of flight upon which the wings are independently tilttable, the pivots of said wings being located one at the advancing and one at the following edge of each plane and so relatively located that when the outer ends of the wings are tilted upwardly the positive angle of incidence of the wings is increased and means carried by the inner ends of the wings for independently warping the wings, as and for the purpose set forth. 80
10. An aeroplane comprising a main plane, tilttable supporting wings, with pivots trending in the line of flight which wings are adapted to be independently tilted by change of the center of gravity of the machine, and means coöperating with said wings to restore them to normal position and reëstablish equilibrium when they have been so tilted, said pivots for each wing being located one at the advancing and the other at the following edge of the wings and at different horizontal planes, for the purpose set forth. 85
11. In an aeroplane, the combination with laterally projecting wings, of pivots arranged on axes trending in the line of flight, whereon the wings are loosely mounted, and inwardly beyond which they extend, fixed posts to which the inner ends of the wings are connected through springs and a warping device so connected with each wing and its post as to vary the angle of incidence and the point of resistance as desired. 90
12. In an aeroplane, the combination with a central body frame and a main plane, of a laterally projecting wing loosely pivoted to the main frame on an axis trending in the line of flight and extending inside of said axis, a spring post at the inner end of said wing, a follower with which said wing is connected, a manually controlled warping device connected to said wing and the spring post by which said wing may be warped to vary its angle of incidence and its point of resistance to forward flight. 95
13. In an aeroplane, the combination with a central body frame and main plane, of laterally projecting wings loosely pivoted

- to the body frame on axes trending in the line of flight and extending inside said axes, spring posts at the inner ends of said wings, followers within said posts, quadrilaterally arranged levers hingedly attached to the inner ends of the wings at diagonally opposite pivots, upper and lower levers fulcrumed upon the remaining two pivots of the quadrilateral levers, the upper lever extending to a hinge connection with the following lower and the lower lever to a sliding connection with the post, and means for oscillating said upper and lower levers in opposite directions relatively to the wing.
14. In an aeroplane, the combination with a central body frame and a main plane, of a laterally projecting wing loosely pivoted to the body frame on an axis trending in the line of flight and extending inside of said axis, a spring post at the inner end of the wing, a follower within said post, a guide on the wing loosely engaging said post and permitting the wing to swing vertically, a quadrilateral link movement secured to the inner end of the wing by two of its diagonally opposite pivots, levers fulcrumed upon the remaining two pivots, one of the levers extending to a hinge connection with the follower and the other to a sliding connection with the post, and means for oscillating said levers in opposite directions relatively to the wing.
15. In an aeroplane, the combination with a central body frame and main plane, of a laterally projecting wing loosely pivoted to the body frame on an axis trending in the line of flight and extending inside said axis, a spring post at the inner end of said wing, a follower within said post, a quadrilateral link movement secured to the inner end of the wing by two of its diagonally opposite pivots, levers fulcrumed upon the remaining two pivots, one lever extending to a hinge connection with the follower and the other to a sliding connection with the post, and means for oscillating said levers in opposite directions relatively to the wing.
16. In an aeroplane, the combination with a central body frame and main plane, of a laterally extending wing loosely pivoted to the body frame on an axis trending in the line of flight and extending inside of said axis, a spring post at the inner end of the wing, a follower within the post, a guide on the wing loosely engaging said post and permitting the wing to warp and tilt under applied force, a quadrilateral link movement secured to the inner end of the wing by two

of its diagonally opposite pivots, levers hinged to the remaining two pivots, one extending to a fulcrum connection with the follower and the other to a fulcrum and sliding connection with the post, a rack secured to the wing, a hand lever pivoted to the wing and locking with the rack, a link extending from the hand lever at one side of its pivot, to the power arm of the lever which extends to the follower and a second link extending from the hand lever, at the other side of its pivot, to the power arm of the lever which extends to the sliding connection with the post, whereby the wing may be warped by power applied to the hand lever.

17. In an aeroplane, a supporting and controlling wing pivoted between its ends at its advancing and following edges, with means at the inner ends of the wing for warping the wing, and flexible truss members for stiffening the wing, movable relatively to fixed parts of the wing to permit such warping.

18. In an aeroplane, a supporting and controlling wing pivoted between its ends at the advancing and following edges, with means at the inner end of the wing for warping the wing, flexible truss members for stiffening the wing, comprising a post extending above and below the wing, and pairs of flexible truss members above and below the wing, each member of each pair being attached at one end to the inner end of the wing near one edge thereof and trained intermediate its ends about said post and attached at its end to the outer end of the wing at the same edge thereof.

19. In an aeroplane, a supporting and controlling wing pivoted between its ends at its advancing and following edges, with means at the inner ends of the wing for warping the wing, flexible truss members for stiffening the wing, movable relatively to fixed parts of the wing to permit such warping and a stiffening truss at the following margin of the wing.

20. In an aeroplane, the combination with a lateral wing pivoted on an axis trending in the line of flight and extending inside of said axis, of a central upstanding post located in the line of said axis, and wires or cords attached to the inner corners of the wing, above and beneath, thence carried to seats in the ends of the post, thence to the outer corners on the same edge and surface from which they were led, and drawn taut, to form a truss, for the purpose set forth.

21. In an aeroplane, the combination with a lateral wing pivoted on an axis trending in the line of flight and extending inside of said axis, of a central, upstanding post located in the line of the axis, wires or cords attached to the inner corners of the wing, above and beneath, thence carried over seats

in the ends of the post and to the outer corners on the same edge and surface from which they were led and drawn taut, and a second wire or cord led from one edge of 5 the wing, in the pivotal line, over the post and to the other edge of said wing.

22. In an aeroplane, the combination with a lateral wing pivoted on an axis trending in the line of flight and extending inside of 10 said axis, of a central upstanding post located in the line of the axis, wires or cords attached to the inner corners of the wing, above and beneath, thence carried over seats in the ends of the post and to the outer corners 15 on the same edge and surface from which they were led and drawn taut, a second wire or cord led from one edge of the wing, in the pivotal line, over the post and to the other edge of said wing and a turn 20 buckle whereby the cords or wires are drawn taut.

23. In an aeroplane, the combination with a lateral wing pivoted upon an axis trending in the line of flight and extending inside 25 said axis, of a central, upstanding post having sleeves upon the ends, with ears or guards thereon, located in the line of said axis, wires or cords attached to the inner corners of the wing, above and beneath, 30 thence carried over said sleeves between the guards thereof, and to the outer corners of the same edge and surface from which they were led, and drawn taut, a cap or plate laid over the sleeves and confining the wires, 35 an eye-screw securing the cap in place, a second wire or cord led from one edge of the wing, adjacent the pivotal line, through the eye of the confining screw on the corresponding edge of the post, to the other edge 40 of the wing.

24. In an aeroplane, the combination of the central body plane, the main plane thereon, the laterally extending wings pivoted to the body frame on axes trending in the line 45 of flight and extending inside their pivots and trussed by wires or cords and posts in the manner described, and means at the inner ends of said wings for warping said wings.

25. In an aeroplane, the combination of the central body frame, the main plane supported thereon, the laterally extending wings loosely pivoted to the body frame on axes trending in the line of flight, and extending inside of said axes, means upon the body frame 55 yieldingly resisting the departure of said wings from the horizontal and tending to restore them to equilibrium when either of them so departs, an arm projecting upward from the rear or trailing edge of the wings at the pivotal point and suitably braced therefrom, and a pivotal connection between the upper end of this arm and the body frame, whereby an outward movement 60 of 65 is imparted to said trailing edge on the low-

ering of the inner end of the wing, or tilting of the same, thus changing the angle of incidence and giving the wing more drag for balancing or turning purposes.

26. In an aeroplane, the combination with 70 a central body frame, a main plane supported thereon, laterally extending wings pivoted to the body frame on axes trending in the line of flight, and extending inside of said axes, means on the body frame yieldingly resisting the departure of the wings from the horizontal and tending to restore them to equilibrium when either so departs, 75 an elevator plane pivoted to the front of the body frame, and means connecting the elevator plane with each wing in such a manner that the up and down action of either wing operates to regulate the elevator plane to different positions.

27. In an aeroplane, the combination of 80 a central body frame, a main plane supported thereon, laterally extending wings pivoted to the body frame on axes trending in the line of flight and extending inside of the said axes, means on the body plane yieldingly resisting the departure of said wings from the horizontal and tending to restore them to equilibrium when either of them so departs, 85 an elevator plane pivoted to the front of the body frame, a lever for operating said plane, a cross bar attached to said lever to rock thereon, and extending to a point over the inner end of each wing, and flexible connection between said wings and the corresponding end of the cross bar, 90 whereby the up and down movement of either wing acts to move the elevator to different positions and to give double extent of movement when both wings are moved in unison. 95

28. In an aeroplane, the combination of 100 a central body frame, a main plane supported thereby, laterally extending wings pivoted to the body frame on axes trending in the line of flight, means on the body frame yieldingly resisting the departure of said wings from the horizontal and tending to restore them to equilibrium when either of them departs, independent foot levers for the feet of the aviator, and a connection between each foot lever and the inner end of the adjacent wing, whereby side movements and up and down flight may be controlled by the feet, leaving the body and hands free for other work. 110

29. In an aeroplane, the combination of 115 a central body frame, a main plane supported thereby, laterally extending wings pivoted to the body frame on axes trending in the line of flight, means on the body frame yieldingly resisting the departure of said wings from the horizontal and tending to restore them to equilibrium when either of them departs, independently pivoted stirrups to receive the feet of the aviator, a 120

125 130 135

lever arm extending from each stirrup, and
flexible connections between said lever arms
and said resisting and restoring mechanism,
whereby the resisting means may be over-
5 come and the position of either wing con-
trolled through the appropriate stirrup.

In testimony, that I claim the foregoing

as my invention I affix my signature in the
presence of two witnesses, this 30th day of
January, A. D. 1912.

DE BERT HARTLEY.
